ESCUTCHEON PLATE

Raymond U. H. Tegner, Rockford, Ill., assignor to
Amerock Corporation, Rockford, Ill.

Filed Jan. 10, 1972, Ser. No. 216,869

Term of patent 14 years

Int. Cl. D8—09

U.S. Cl. D8—179

Fig. 1.

Fig. 2.

Fig. 3.

Fig. 4.

FIG. 1 is a side view of an escutcheon plate incorporating my new design and embodied in a plate for supporting a knob.

FIG. 2 is a front view of the plate shown in FIG. 1 and taken along the line 2—2 in FIG. 1.

FIG. 3 is a sectional view taken along the line 3—3 in FIG. 2.

FIG. 4 is a sectional view taken along the line 4—4 in FIG. 2.

FIG. 5 is a side view of an escutcheon plate incorporating my new design and embodied in a plate for supporting a pull.

FIG. 6 is a front view of the plate shown in FIG. 5 and taken along the line 6—6 in FIG. 5.

FIG. 7 is a sectional view taken along the line 7—7 in FIG. 6.

The portions shown in broken lines form no part of the design.

I claim:

The ornamental design for an escutcheon plate, as shown and described.
